US0D1108642S

(12) **United States Design Patent** (10) **Patent No.:** **US D1,108,642 S**
(45) **Date of Patent:** **** Jan. 6, 2026**

(54) **KNEE PAD**

(71) Applicant: **Milwaukee Electric Tool Corporation**,
Brookfield, WI (US)

(72) Inventors: **Trent T. Bauters**, West Allis, WI (US);
Scott M. Hangartner, Richfield, WI (US); **Emelie E. Troedson**, Seattle, WA (US)

(73) Assignee: **Milwaukee Electric Tool Corporation**,
Brookfield, WI (US)

(**) Term: **15 Years**

(21) Appl. No.: **29/932,013**

(22) Filed: **Mar. 11, 2024**

Related U.S. Application Data

(60) Continuation of application No. 29/868,453, filed on Dec. 2, 2022, now Pat. No. Des. 1,025,498, which is a division of application No. 29/730,276, filed on Apr. 2, 2020, now Pat. No. Des. 973,970.

(57) **CLAIM**

The ornamental design for a knee pad as shown and described.

DESCRIPTION

FIG. 1 is a front top perspective view of a knee pad showing our new design;

FIG. 2 is a rear top perspective view of the knee pad in FIG. 1;

FIG. 3 is a rear bottom perspective view of the knee pad in FIG. 1;

FIG. 4 is a second rear top perspective view from below of the claimed design of the knee pad in FIG. 1;

FIG. 5 is a front view of the knee pad in FIG. 1;

FIG. 6 is a rear view of the knee pad in FIG. 1;

FIG. 7 is a left side view of the knee pad in FIG. 1;

FIG. 8 is a right side view of the knee pad in FIG. 1;

FIG. 9 is a top view of the knee pad in FIG. 1; and,

FIG. 10 is a bottom view of the knee pad in FIG. 1.

The broken lines in the drawings depict portions of the knee pad that form no part of the claimed design.

1 Claim, 10 Drawing Sheets
